UNITED STATES PATENT OFFICE.

CHARLES N. WADE, OF PATERSON, NEW JERSEY.

TRANSFER-PRINTING MACHINE.

Application filed June 23, 1922. Serial No. 570,334.

To all whom it may concern:

Be it known that I, CHARLES N. WADE, a citizen of the United States, residing at Paterson, in the county of Passaic and State of New Jersey, have invented certain new and useful Improvements in Transfer-Printing Machines, of which the following is a specification.

This invention is a machine for printing 10 tickets and is intended more particularly for use upon street cars for printing transfers, although it is adapted for use in other places, as for printing tickets of admission to places of amusement, soda water checks, 15 and similar slips. The invention has for its object the provision of a compactly arranged mechanism by the use of which indicia may be printed upon paper fed from a roll and the printed portion severed for 20 delivery to the passenger or customer. A further object of the invention is to provide means whereby certain indicia to appear upon the ticket may be changed at will so as to properly denote the date and time 25 of issue, the period in which the ticket will be valid, and the direction of travel in which it will be acceptable as well as other data required in the operation of railways. A further object of the invention is to provide 30 a mechanism which may be operated from either side of the machine and which can only be operated in the proper direction. Other incidental objects of the invention will appear in the course of the following 35 description.

One embodiment of the invention is illustrated in the accompanying drawings, in which—

Figure 1 is a perspective view of my im- 40 proved ticket-printing machine;

Fig. 2 is a side elevation with the casing removed;

Fig. 3 is a view similar to Fig. 2 but showing the opposite side of the mechanism;

Fig. 4 is a central longitudinal section;

Fig. 5 is a bottom plan view;

Fig. 6 is a bottom plan view of the printing devices and the means for operating the same;

Fig. 7 is a transverse section on the line 7—7 of Fig. 4;

Fig. 8 is a detail perspective view of the ribbon-feeding mechanism;

Fig. 9 is a detail perspective view of the 55 means for reversing the ribbon feed;

Fig. 10 is a detail perspective view of the counter-operating mechanism;

Fig. 11 is a detail perspective view of the permanent printing plate viewed from the 60 upper side;

Fig. 12 is a detail section showing the means for locking the handle against accidental movement;

Fig. 13 is a detail section of a locking pin 65 employed in certain parts of the mechanism;

Fig. 14 is a detail perspective view showing the manner of securing the movable knife;

Fig. 15 is a plan view of a transfer ticket 70 which may be issued by the machine.

The mechanism of my invention is housed within a casing 1 suitably shaped to enclose all the working parts except the operating handle 2 and equipped at one end with a 75 delivery opening 3 through which the printed ticket is issued. The casing is preferably constructed in two members, the upper member being locked to the lower member so as to prevent unauthorized access to the 80 working parts, a lock being indicated at 4 in Fig. 1. This lock may be of any well-known construction. The top of the casing is provided with a sight opening 5 to permit reading of the counter so that the number of transfers issued may be noted at any time and it is also provided in its top with a plurality of longitudinal slots 6 through which the setting levers 7 project, indicating plates 8 being secured upon the top of the casing adjacent the several slots and bearing indicia corresponding to the matter controlled by the levers extending through the respective slots.

Within the casing is disposed a supporting frame comprising a lower portion 10 which is equipped with attaching plates or feet 11 whereby it may be rigidly secured to the bottom of the casing and an upper portion 12 which is connected with the lower portion at one side by a hinge 13 whereby the upper portion of the frame and the mechanism carried thereby may be swung over to the side of the lower portion to facilitate the placing of the end of a paper web in the printing position and also to facilitate the renewing of the printing ribbon and permit examination of the printing surfaces. Projecting from one end of the lower portion 10 of this frame are arms 14 be- 105 110

tween the free ends of which is mounted the paper web 15, the said web being carried by a spindle 16 rotatably mounted in the ends of the said arms and held against accidental withdrawal by a latch 17 pivotally mounted upon one of the arms and held in engagement with an annular groove in the adjacent end of the spindle by a spring 18 in an obvious manner. Standards 19 are secured to and rise from the arms 14 and a counter 20 is carried by the upper ends of the said standards, this counter being of a well-known type and purchased by me in the open market. The counter is actuated by a step by step ratchet-feeding mechanism mounted upon a counting shaft extending through the counting mechanism and equipped at one end with a crank arm 21 to which is pivoted the upper end of a connecting rod 22, the lower end of said connecting rod being pivoted to the rear end of an operating lever 23 which is pivotally mounted intermediate its ends upon the frame 10 and has its forward end resting upon a tappet 24 secured to the main operating shaft 25 which is journaled in and extends transversely through the frame 10. The said operating shaft 25 is of sufficient length to project beyond the frame at both sides thereof and extend through the sides of the casing, and its extremities are angular in cross section, as clearly shown in Figs. 2 and 3, so that either extremity may be engaged by the operating handle 2 to permit the operation of the machine from either side. It will be readily understood that each rotation of the main shaft 25 will cause the tappet 24 to rock the lever 23 once and will thereby actuate the counter so that an accurate count of the number of revolutions of the shaft will be made, the total result being readable through the sight opening 5 in the casing. As a transfer is printed at each revolution of the main shaft, it is obvious that the conductor or other official will be informed at all times of the number of transfers or tickets which have been printed.

The paper web 15 is fed from the roll over a bed plate or platen 26 disposed longitudinally within the lower frame 10 and adjacent the upper edge thereof, the said bed plate or platen being of such dimensions that it will fit closely between the sides of the frame 10 and being equipped on its edges near its ends with studs 27 playing in grooves 28 in the sides of the frame so that the platen will be guided vertically in its movements. The platen rests upon tappets or cranks 29 which are carried by a transverse shaft 30 and by the main driving shaft 25 respectively, mounted in the sides of the frame 10 at such points that they will be vertically below the opposite end portions of the platen and the tappets or cranks are so

disposed that they will always be in parallelism and will thereby act upon the platen simultaneously so that it will be supported in a horizontal plane at all times. Rollers 31 are fitted in the ends of the tappets to 70 reduce the frictional wear between the same and the platen. At the side of the frame remote from the tappet 24 and the rocking lever 23, the main shaft 25 is equipped with a gear 32, and the transverse shaft 30 is 75 equipped with a like gear 33, these gears meshing with an idler 34 disposed between them and carried by a shaft 35 which is also journaled in the sides of the frame 10 and is equipped at its center with a crank or 80 tappet 36, the purpose of which will presently appear. It will now be understood that, when the main shaft 25 is rotated, the shaft 30 will be rotated in unison therewith and the tappets or cranks 29 caused to describe 85 a complete revolution and thereby raise the platen 26 so as to carry the paper resting thereon against the printing faces, the platen being held to the tappets and caused to descend as the tappets move downwardly 90 by a spring 37 secured at one end to a pin or rod 38 within the frame 10 and at its upper end to a pin or stud 39 rigid with the platen and depending therefrom. A feed roller 40 is mounted between the sides of 95 the frame 10, adjacent the front end of the platen, and bears against the under side of the paper, as clearly shown in Fig. 4. This feed roller may be of any well-known form and is equipped at its ends with trunnions 100 fitted in the sides of the frame 10, the trunnion at that side of the frame carrying the counter-actuating lever 23 being equipped with a pinion 41 which is at times actuated by a mutilated gear 42 secured upon the 105 main driving shaft 25, as shown in Fig. 3. The parts are so timed that during the printing period, the feed roller will be at rest, but after the ticket has been printed, the teeth of the gear 42 will mesh with the teeth 110 of the pinion 41 and will actuate the same so that the printed portion of the paper will be fed through the machine and its end projected through the delivery opening 3 in the casing. A small pressure roller 43 is 115 mounted in the frame immediately over the feed roller 40 and bears upon the paper to cooperate with the feeding roller in effecting movement of the paper over the platen in an obvious manner. At the rear end of 120 the machine, a small guide roller 44 is provided above the path of the paper so that, as the diameter of the roll of paper decreases, the paper will be held to a horizontal plane as it assumes a position over the 125 platen and will be prevented from rubbing against the printing ribbon.

Below the feed roller and the shafts 25, 30 and 35, I provide a rocker 45 consisting of a plate secured between its ends to a 130

rocker shaft 46 journaled in the sides of the frame 10, the inner or rear end of the rocker 45 being disposed in the path of the tappet or crank 36 and being held to said tappet by a spring 47 which is secured at its lower end to a cross rod 48 which also constitutes a brace for the frame, and at its upper end the said spring is attached to the front end of the rocker. The front end of the rocker 10 is constructed with lugs 49 projecting through openings 50 in the lower portion of the movable knife 51 so that as the rocker is actuated the knife will be caused to reciprocate. The knife is obviously capable 15 of a limited rocking movement relative to the rocker and it is held to the end of the rocker by a retaining spring 52 of the form shown clearly in Fig. 4. The said spring consists of a resilient plate secured at one 20 end to the under side of the rocker, thence extending downwardly and forwardly under the lower end of the knife and then upwardly in front of the knife to constitute a bracing finger 53 bearing against the front 25 side of the knife near the upper cutting edge thereof. This knife cooperates with a similar stationary knife 54 which is secured rigidly upon the end of the frame 10, and a small guide rod 55 is preferably disposed 30 below the stationary knife so as to prevent dropping of the end of the paper after a printed ticket has been severed therefrom.

The several printing instrumentalities are mounted in and carried by the upper 35 frame 12 which also carries the printing ribbon 56. This printing ribbon is carried by spools 57 rotatably mounted at the ends of the frame and retarded in their movements by presser springs 58 which are secured to the ends of the frame and bear upon the ends of the spools, as shown and as will be readily understood. The ends of the ribbon are secured to the hubs of the spools and the ribbon is wound upon one 40 spool and simultaneously unwound from the other spool in the operation of the machine, its intermediate portion being passed under small transverse guide rods 59 at the ends of the frame so that the ribbon will 45 be parallel to the platen and the paper resting thereon. As shown most clearly in Fig. 8, each ribbon spool is equipped at one end with a ratchet disc 60 and adjacent each ratchet disc is a feeding pawl 61 which 50 is adapted to engage and actuate the respective ratchet. Each pawl 61 is pivotally mounted upon a supporting arm 62 arranged adjacent the respective ribbon spool and having its end encircling the spindle of 55 the spool. One end of the supporting arm 62 extends upwardly and the said upwardly extending portions are connected by a strap or bar 63 disposed adjacent the side of the frame 12, the two arms 62 and the connecting bar or strap 63 constituting a feeding 60 frame which is actuated by a rocking lever 64 fulcrumed upon the side of the frame 12 and constructed at its lower end with a yoke or stirrup 65 within which is disposed an eccentric 66 carried by the shaft 35 at the 65 outer side of the idler gear 34. The upper end of the rocking lever 64 is provided with a longitudinally extending slot 67 in which is engaged a pin or stud 68 on the inner side of the connecting bar 63. It will 70 be readily seen that the rotation of the shaft 35 and the eccentric 66 carried thereby will effect oscillation of the lever 64 through the engagement of the eccentric with the inner sides of the yoke 65 and the upper end of the lever will, of course, be thereby actuated so that through its pin and slot engagement with the bar 63 said bar will be shifted endwise and the arms 62 caused to rock about 75 the spindles of the ribbon spools as their respective centers. Slidably mounted upon the bar 63 and held thereto by pins or studs 68 passing through longitudinal slots 69, is a shifter bar 70, the length of which is less than that of the bar 63 so that the shifter 80 bar cannot be in contact with both pawls 61 at the same time. When the end of the shifter bar 70 bears against the upper end of the adjacent pawl 61, the said pawl 61 will be held out of engagement with the adjacent ratchet 60 and, consequently, will be inoperative but the pawl at the opposite end of the machine will be in operative position 85 and will be held in engagement with the adjacent ratchet by the spring 71 attached at 90 its opposite ends to the end of the pawl and to the shifter bar 70, respectively, as shown clearly in Fig. 8. Consequently, when the bar 63 is reciprocated in the described manner, the operative pawl 61 will describe an 95 arc concentric with the adjacent ratchet and will, therefore, partly rotate the ratchet and the ribbon spool spindle to which it is secured so as to effect feeding of the ribbon. To maintain the shifting bar in a set position, a dog 72 is secured upon the shifter bar and consists of a leaf spring having 100 its free end properly shaped to engage one of the recesses or notches 73 in the upper edge of the bar 63. The engagement of the dog with a recess 73 prevents movement of the shifter bar independently of the feed bar until such time as the shifter bar is independently actuated by the reversing 105 mechanism. A reversing bar 74 is arranged 110 parallel with and below the shifting bar 70 and is attached thereto by a lip or lug 75 disposed against the outer side of the shifter bar and having fastening screws 76 inserted therethrough into the shifting bar, as will 115 be readily understood. At or adjacent the ends of the reversing bar 74, are pins or studs 77 which play in slots or notches 78 in upstanding arms 79 of reversing levers 120 80. The reversing levers 80 are pivotally 125

mounted upon the side of the frame 12 adjacent the ribbon spools and one lever extends outwardly under the end of the adjacent spool and at its extremity is provided with a presser plate or finger 81 projecting under the spool and adapted to bear against the ribbon wound thereon. The reversing lever, at the opposite end of the machine, is provided at its outer end with an upstanding branch 82 from which a presser plate or finger 83 projects over the adjacent spool to bear upon the ribbon wound thereon. When the ribbon starts to wind upon either spool, the adjacent presser plate or finger will be out of contact with the ribbon. As the winding of the ribbon continues, however, and the diameter of the wound portion increases, the ribbon will eventually be brought to bear upon the adjacent presser plate or finger and when the diameter of the wound ribbon reaches a predetermined length, the pressure exerted by the ribbon upon the adjacent presser finger or plate will move the same outwardly from the spindle of the ribbon spool and will thereby rock the reversing lever so that the end of the slot or notch 78 engaging the stud 77 will exert a pull upon the reversing bar 74 which will move the shifting bar 70 endwise and thereby discontinue the contact between one end of said shifting bar and the adjacent pawl and cause the opposite end of said bar to bear upon the pawl respectively adjacent to it so that the direction in which the ribbon will feed will be automatically reversed. While the springs 58 will prevent excessively rapid rotation of the ribbon spools and will thereby tend to hold the ribbon taut at all times, I provide additional means to attain this end in a coiled spring 84 extending between the projecting ends of the ribbon spool spindles and having its ends attached to collars 85 fitted upon the ends of the ribbon spool spindles and held frictionally thereto. I thus effectually prevent slipping of the ribbon during the feeding operation.

Secured to the lower edges of the upper frame 12 is a plate 86 provided with transverse slots or openings 87 therethrough to accommodate printing faces which are intended to print through the ribbon onto the paper when the platen is raised. Certain type faces are formed on or secured rigidly to the under side of this plate 86 as will be noted on reference to Fig. 6. Disposed longitudinally of the plate near one side edge thereof is a printing bar or strip 88 having numbers formed thereon in proper succession which are intended to print upon the ticket, shown at 89, the numerals 90 indicative of zones through which the issuing car may travel. Adjacent one end of the said bar 88, and disposed transversely of the plate 86, is a printing plate 91 which will

print the word "Zone" upon the ticket, as shown at 92. A transverse printing plate 93 is also carried by the under side of the plate 88 and this printing plate 93 has formed thereon faces which will print upon the transfer the number of the machine, as indicated at 94 in Fig. 15. The name of the company controlling the service, indicated at 95, will be printed upon the ticket by a printing plate 96 secured to the under side of the plate 86 between two of the openings 87 therein and at one end of the plate is secured a printing plate 97 which will print the current year upon the ticket, as shown at 98. Mounted within the upper frame 12, adjacent one end thereof and arranged to print upon the ticket at the top thereof, is a numbering device 99 which may be of any detailed construction of any well-known type. The abbreviation "No." is carried by a plate 100 secured at one end of the casing for the numbering device and is adapted to register with the line of numerals displayed at the bottom of the numbering machine by the digit wheels therein. The actuating means for the digit wheels are controlled by a fork 101 which is slideable in the end of the casing of the numbering machine and is pivoted at its upper end to a lever 102 fulcrumed at its inner end upon a bracket 103 secured to the side of the frame 12 and having its opposite end projecting through the opposite side of the frame to bear upon the upper end of a push rod, 104 disposed between the side of the frame and the ribbon-feeding bar 63 and held to the frame and guided in its movement by a keeper or sleeve 105 secured on the side of the frame. The lower end of this pusher or lifter 104 rests upon and is supported by a rocking lever 106 which is fulcrumed upon the side of the frame 10 below the shaft 35 and has its opposite end in contact with a cam 107 carried by the main driving shaft 25, as shown clearly in Fig. 2. The numbering machine is held in position upon the plate 86 by a bracket 108 secured upon the plate and extending over the top of the numbering device, as shown in Fig. 4. It will be readily understood that each revolution of the main driving shaft will cause the cam 107 to impart one rocking movement to the lever 106 and will lift the member 104 so as to raise the lever 102 and thereby draw the yoke 101. The upward movement of the said yoke will actuate the digit wheels of the numbering machine so that the number to be printed thereby will be advanced one unit.

Disposed between the numbering machine and the front end of the frame 12, a plurality of changeable printing devices are supported within the said frame. Each of these printing devices comprises a drum 109 having printing strips 110 secured about its

5 peripheral surface, and each drum is loosely mounted upon a shaft or rod 111 carried by the sides of the frame. To one end of each drum is secured a gear 112 and this gear is 10 in mesh with a segment or rack 113 on the lower end of a setting lever 7 which is fulcrumed upon a shaft or rod 114 mounted in the upper portions of the side bars of the frame 12. It will be readily understood 15 that by rocking any lever 7, the segment or rack 113 at the lower end thereof, meshing with the gear 112, will effect rotation of the adjacent printing drum so that any desired 20 type face or printing strip on said drum may be brought to the lowest point of the 25 drum which is the printing point. As shown in Fig. 4, the type face on the drum which is to print will be disposed within one of the 30 openings 87 in the plate 86 and the type 35 face will project through the opening so as to lie in the same plane as the several type faces carried by the plate 86. The several 40 setting levers 7 work alongside arcuate locking bars 115 which are fixedly mounted upon 45 the frame 12 and in which are formed 50 openings or sockets 116 adapted to be engaged by locking pins or plungers 117 slidably fitted in tubular casings 118 carried by the upper free ends of the setting levers. 55 The locking pins or plungers are each formed with a head 119 having a slightly convex under surface and a spring 120 housed within the tubular casing 118 bears upon the plunger or locking pin to hold it to the locking bar 115 so that the pin or plunger may ride over the bar readily but will be instantly projected into a socket 116 with which it may register. The plunger or pin, of course, yieldably engages the 60 socket so that a slight manual force exerted upon the setting lever will carry the same to the desired point, but when the moving force is released from the lever, the pin will engage the socket with sufficient strength to 65 effectually hold the lever against accidental displacement and the printing drum will thus be held in the position in which it may be set. The several changeable printing devices are alike in construction and arrangement 70 so that the description just given applies equally to all, the only difference between the several devices being in the matter printed by the respective type faces. The setting levers are offset intermediate 75 their ends, as shown at 121, so as to accommodate the levers to the locking bars and permit the shifting gears to be brought within a small compass as well as to avoid interference between the levers of one series 80 and those of another series. As the several gears 113 are thus brought close together, the offset portions of some of the levers in extreme positions will tend to bear upon the straight edges of adjacent gears and to accommodate this position some of the gears 85

are provided with notches 122 in their upper edges in which the offset portions of the levers may be received in the said extreme positions. One of the printing drums carries type faces which by their contact with the printing ribbon will print upon the paper the hour of issue of the transfer, while an adjacent drum will print the minutes of the issue so that the exact time when the transfer was given to the passenger will be 90 displayed thereon. Another printing drum is adapted to place upon the ticket the designations "A. M." "P. M." "Noon" or "Night." The day of the week, the month, and the day of the month are also displayed upon the printed ticket and to avoid the necessity of employing a drum of unwieldy size for printing the days of the month, I prefer to employ two drums, one of which will print the first fifteen days and the other 95 of which will print the remaining days of the month. One drum will print below the words "Zone" upon the ticket, the number of the zone in which the ticket is issued, and, where the zone system is now used, the 100 ticket is delivered to the passenger when he enters the car, and, when he leaves, the marginal number indicating the zone in which he leaves will be punched by the conductor, the ticket being then retained by the conductor for use in his accounting to the company. One of the printing drums will print the word "Change" upon the ticket while another will print the direction in which the transfer may be used. 105

To retain the upper and lower frames in their proper assembled relation and prevent the upper frame swinging about the hinge 13, locking bolts 123 are inserted through the lower frame and through projections 124 on the upper frame. When the upper frame is to be swung over upon the lower frame so as to permit the insertion of a new web of paper or the changing of new ribbon, these locking bolts are withdrawn as is obvious. 110

As previously stated, the machine may be operated from either side and the handle 2 is, therefore, removable and may be fitted to either end of the main driving shaft 25. Upon the casing, I provide a stop latch 125 which may conveniently be an arm pivoted upon a suitable lug on the inner side of the casing and having a tooth 126 projecting through a suitable opening in the casing below the end of the driving shaft. A push button 127 projects from the latch through the side of the casing adjacent the free end of the latch so that a slight pressure by the hand of the operator upon the button will force the latch inwardly against the tension of a spring 128 carried by the casing and bearing against the free end of the latch, as shown clearly in Fig. 12. The spring 129 holds the tooth 126 in the path of the handle 130

2 so that, if a single ticket is to be printed, the handle will be permitted to make only one revolution. When, however, several tickets are to be issued, the conductor will 5 press upon the button 127 until the handle has cleared the tooth 126 so that a second revolution may be made. A similar latch 129 is provided and, as shown clearly in Fig. 12, this latch is spaced from the latch 125 a 10 distance approximately equal to the thickness or width of the handle 2. When the handle is at rest, its opposite edges will be engaged by the latches so that accidental movement of the handle will be prevented. 15 Moreover, the latch 129 will positively prevent reverse rotation of the handle and disarrangement of the operating mechanism will be thereby avoided. The front edge of the latch 129 is tapered, as shown at 130, 20 so that, when the handle is rotated in the proper direction to print a ticket as it completes its revolution, it will ride upon the said tapered portion and force the latch inwardly against the tension of the spring 131 25 so that it may be brought to rest in its initial position against the tooth 126.

In the use of the device, the printing drums are set to print the desired data and the position of the drums will be, of course, 30 determined by the position of the setting levers relative to the respectively adjacent display or indicator plates 8 upon the casing. The crank 2 is then given one complete rotation and this rotation will effect feeding of 35 the paper through the machine, the severing of the printed ticket and the feeding of the ribbon. The main driving shaft and the shaft 20 will be rotated in unison by the gearing shown and described and the platen 40 will be thereby lifted so as to carry the paper against the ribbon and press both the paper and the ribbon against the type faces above the ribbon. The platen is then lowered and as it recedes from the ribbon and the printing faces, the printed portion of the paper is fed over the platen and between the knives and to and through the delivery opening 3 in the casing, the printed slip being severed by the rising knife 51 just before the 45 parts return to their initial position. The operation may be repeated as rapidly as may be needed and as often as may be needed as long as a supply of paper remains.

Having thus described the invention, what 50 is claimed as new is:

1. The combination of a platen, means for printing upon a paper strip resting on the platen, a stationary knife disposed adjacent one end of the platen, means for feeding the 55 paper strip over the platen and past said knife, a rocker disposed below the platen, a movable knife loosely fitted upon and carried by one end of said rocker and arranged to cooperate with the stationary knife, a 60 resilient holding member secured to the

rocker and bearing yieldably upon the outer face of the movable knife, and means for actuating said rocker.

2. The combination of a platen, means for printing upon a paper strip resting on the 70 platen, a stationary knife disposed adjacent one end of the platen, means for feeding the paper strip over the platen and past said knife, a rocker arranged below the platen, a movable knife loosely fitted upon one end of said rocker and cooperating with the stationary knife to sever a printed portion of the paper strip, a transverse shaft between the platen and the inner end of the rocker, a tappet on said shaft bearing upon the inner end of the rocker, and a retractile spring 75 acting upon the outer end of the rocker.

3. The combination of a supporting frame provided with vertical grooves in its inner sides at its upper end, a platen disposed between the sides of the frame and provided with studs engaging said grooves, means for feeding a paper strip over said platen, printing members disposed above the platen, a pin depending from the platen, a spring 80 secured to said pin and acting thereon to hold the platen normally lowered, operating shafts disposed below the platen, tappets on said shafts provided at their free ends with rollers adapted to bear against the under side of the platen, and means for actuating said shafts whereby to move the platen and the paper strip resting thereon to the printing members.

4. The combination of a platen, printing members disposed above the platen, means for feeding a paper strip over the platen, means for raising and lowering the platen whereby to carry the said paper strip to and from the printing members, a counting device, a rocking lever pivoted between its ends upon the frame and connected at one end with the counting device, a driving shaft controlling the movement of the platen and of the paper strip, and a tappet upon 105 said shaft arranged to bear against the free end of said rocking lever whereby the counting device will be actuated at each movement of the platen.

5. In a ticket-printing machine, the combination of a supporting frame, a platen mounted in said frame, printing drums disposed within the frame above the platen, a printing ribbon arranged between the printing drums and the platen, means for feeding a paper strip over the platen, means for moving the platen to and from the printing drums, guiding and holding arms upon the upper portion of the frame provided with 110 sockets therein, setting levers mounted on the upper portion of the frame adjacent the respective guiding and holding arms, gearing connecting said levers with the respective printing drums, and plungers carried 115 by the said levers and yieldably engaging 120

the sockets in the respectively adjacent guiding and holding arms.

6. In a ticket-printing machine, the combination of a supporting frame, a platen 5 mounted in the lower portion of the frame, printing members disposed above the platen, one of said members constituting a numbering device and including changeable type faces and a fixed type face, a setting element 10 for the movable type faces of the numbering device slidably mounted at the end of said movable type faces, a lever pivotally mounted upon the frame above the numbering device and pivoted intermediate its ends 15 to the upper end of said setting element, a pusher slidably mounted upon the frame and bearing against the under side of the said lever at the free end thereof, a driving shaft mounted in the frame below the 20 platen, a cam on said driving shaft, a rocker mounted upon the frame below the shaft and having one end in engagement with said cam and at its opposite end in engagement with the lower end of said pusher, means for 25 feeding a paper strip over the platen, and means driven by said shaft for moving the platen and the paper strip thereon to the printing members.
7. In a ticket-printing machine, the combination of a frame comprising a lower member, an upper member resting on the lower member and hingedly connected thereto at one side, a platen carried by the lower member of the frame, printing members 35 carried by the upper member of the frame, a printing ribbon carried by the upper member of the frame and extending under the printing members, and means housed within the lower portion of the 40 frame for feeding a paper strip over the platen and for moving the platen with the strip thereon toward and from the printing members.
8. The combination of a casing, a frame 45 secured within the casing, a platen mounted within the frame, printing members mounted within the frame over the platen, a driving shaft extending transversely through the frame and having its ends projecting 50 through the opposite sides of the casing, means actuated by said shaft for feeding a paper strip over the platen and for moving the platen toward and from the printing members, a handle to be removably engaged 55 upon either end of the driving shaft, spring-pressed latches mounted within the casing and projecting through the same to engage opposite edges of the handle, and means on one of said latches operable from the exterior of the casing to release the same from the handle, the other of said latches having its edge remote from the first-mentioned latch tapered.
9. In a ticket-printing machine, the combination of a platen, printing members dis- 60 posed above the platen, ribbon-carrying spools mounted at the ends of the printing mechanism, a printing ribbon carried by said spools and extending between the same below the printing members, ratchet discs fixed 70 upon the spindles of said spools, a feeding bar having its ends loosely fitted upon the said spindles adjacent said ratchets, pawls carried upon said feeding bar and adapted to engage the respectively adjacent ratchets, a 75 driving shaft, means controlled by said driving shaft for moving the platen toward and from the printing members and for feeding a paper strip over the platen, an eccentric driven by said shaft, a lever operatively connected at its upper end with the feeding bar and provided at its lower end with a yoke engaging said eccentric, and means mounted on the feeding bar for selectively holding one of said pawls inoperative.
10. In a ticket-printing machine, the combination of a platen, a printing mechanism arranged above the platen, spools disposed at the ends of the printing mechanism, a printing ribbon carried by said spools and extending between the printing mechanism and the platen, ratchets at the ends of the said spools, a feeding bar having its ends loosely mounted concentric with said ratchets, pawls carried by the ends of said feeding bar and adapted to engage the respectively adjacent ratchets, means for selectively holding one of the pawls inoperative, and means controlled by the wound portion of the ribbon for shifting the last-mentioned means whereby to reverse the direction of feed of the ribbon.
11. In a ticket-printing machine, the combination of a platen, a printing mechanism disposed above the platen, spools mounted 100 at the ends of the printing mechanism, a printing ribbon carried by said spools and passing below the printing mechanism, ratchet discs at the ends of the spools, a feeding frame having its ends mounted concentric with said ratchet discs, pawls mounted on the ends of said frame and adapted to engage the respectively adjacent ratchet discs, means for reciprocating the feeding frame whereby to cause either pawl to operate the adjacent ratchet, a shifting bar slidably mounted upon the feeding frame and having its ends arranged to selectively abut the free ends of the ratchets, yieldable connections between the ends of the said shifting bar and the ends of the respectively adjacent pawls, means for shifting said bar, and a dog carried by said shifting bar and adapted to engage the feeding frame whereby to hold the shifting bar in a set position relative to the 105 frame.
12. In a ticket-printing machine, the combination of a platen, a printing mechanism disposed above the platen, spools mounted at the ends of the printing mechanism, a rib- 110 115 120 125 130

bon carried by said spools and extending under the printing mechanism, ratchet discs at the ends of the spools, a feeding frame having its ends concentric with said ratchet discs, pawls carried by the ends of the feeding frame and adapted to engage the respectively adjacent ratchet, means for reciprocating said feeding frame, a shifting bar slidably mounted upon the feeding frame and adapted to selectively hold one of the pawls inoperative, a connecting rod fixed to said shifting bar, angle levers fulcrumed below said connecting rod and provided with slots in their ends adjacent said connecting

rod, studs carried by the said connecting rod 15 and engaging said slots, and presser fingers carried by the said angle levers and arranged adjacent the spools, one of said presser fingers extending over the respectively adjacent spool and the other of said fingers ex- 20 tending along the respectively adjacent spool whereby as the ribbon is wound upon either spool it will bear upon the adjacent finger and actuate the shifting bar to effect reversal of the feed of the ribbon. 25

In testimony whereof I affix my signature.

CHARLES N. WADE. [L. S.]
